VENDING MACHINE FOR CAPSULES

Grant A. Wiswell, San Mateo, Calif.

Application July 28, 1958, Serial No. 51,953

Term of patent 14 years

(Cl. D52—3)

Fig. 1.

Fig. 2.

Fig. 3.

Fig. 4.

Fig. 1 is a front elevational view of a vending machine for capsules, showing my new design;

Fig. 2 is a side elevation;

Fig. 3 is a top plan view; and

Fig. 4 is a perspective view in reduced scale.

The undisclosed side of the vending machine is substantially the same in appearance as the side shown.

I claim:

The ornamental design for a vending machine for capsules, as shown and described.
